Primary Examiner — Clint A Samuel(74) *Attorney, Agent, or Firm* — Kilpatrick Townsend & Stockton LLP(57) **CLAIM**

The ornamental design for a light fixture, as shown and described.

DESCRIPTION

FIG. 1 is a front top perspective view of a light fixture.

FIG. 2 is a front view of the light fixture of FIG. 1.

FIG. 3 is a left side view of the light fixture of FIG. 1.

FIG. 4 is a right side view of the light fixture of FIG. 1.

FIG. 5 is a rear view of the light fixture of FIG. 1.

FIG. 6 is a top view of the light fixture of FIG. 1.

FIG. 7 is a bottom view of the light fixture of FIG. 1; and, FIG. 8 is a front bottom perspective view of the light fixture of FIG. 1.

The dash-dot broken lines represent unclaimed boundary of the claimed design. The dotted broken lines show unclaimed subject matter only and form no part of the claimed design.

1 Claim, 8 Drawing Sheets(56)
